WAVE SIGNALING SYSTEM

William A. MacDonald, Little Neck, N. Y., assignor
to Hazeltine Corporation, a corporation of Delaware

Original application July 21, 1930, Serial No.
469,487. Divided and this application December
12, 1931, Serial No. 580,619. In Canada June
19, 1931

25 Claims. (Cl. 178—44)

This invention relates to radio receiving systems and more especially to multi-stage thermionic receivers tunable over a range in frequency and adapted for the reception of signals 5 within the so-called "broadcast" band of frequencies.

This application is a division of my copending application Serial No. 469,487, filed July 21st, 1930, and issued May 23, 1933 as United States 10 Patent No. 1,910,399.

A primary object of the invention is to provide a radio receiver of the type specified embodying the features of a gang operated multiple attenuator volume control for varying the signal intensity over a wide range of values in a substantially distortionless manner; an overall sensitivity response characteristic varying with frequency in a manner which is under control of the designer; an overall selectivity which is also under 15 the control of the designer but which preferably is maintained substantially constant throughout the tuning range; and an improved audio-frequency characteristic so shaped as to compensate at least in part for the side-band attenuation of 20 the higher audio-frequencies caused by the selectivity characteristics of the radio-frequency tuning system.

Detailed objects are to provide improved coupling circuits for interconnecting the antenna 30 and first thermionic tube or for connecting successive tubes in cascade relation. The individual coupling circuits are adapted to slope the voltage amplification curve for a given stage in a desired manner which is under control of the designer. 35 In the radio-frequency stages the individual coupling circuits are adapted further to control automatically the variation in resonance band width with frequency over the tuning range in accordance with a selected design. In the aggregate, the coupling circuits produce a final 40 sensitivity-response curve of preselected slope, and an audio-frequency characteristic of substantially constant efficiency over the essential range of frequencies for speech and music.

45 A refinement consists in coupling the last radio-frequency amplifier tube to the detector by means of a coupling circuit having a higher voltage amplification ratio than the coupling systems associated with the preceding stages in 50 order to prevent the tube preceding the detector from overloading.

Additional features of the invention will become apparent from the subsequent detailed description when read in conjunction with the appended 55 drawings.

In connection with the coupling circuits described herein, the term "effective" or "resultant" coupling will be used. This will be understood as the total coupling electrostatic as well as electromagnetic existing between the portions of a circuit under consideration. 60

The invention will be best understood by immediate reference to the drawings, wherein Figure 1 shows diagrammatically a complete radio broadcast receiving system in accordance with the present invention, and Figure 2 shows a similar view of a modified circuit. 65

Figures 3, 4 and 5 show various forms of coupling circuits applicable to the present invention. 70

Figures 6, 8, 10 and 11 are graphs illustrative of the operational characteristics of the present invention.

Figures 7 and 9 show diagrammatically the circuits upon which curves of Figures 6 and 8 are 75 based.

Referring to the drawings, the receivers comprise an antenna circuit 1, four thermionic tubes V₁ to V₄, inclusive, operating as stages of radio-frequency amplification and a detector tube V₅, 80 all of the screen-grid heater-element type, interconnected in cascade relation by means of coupling systems or circuits B, C, D and E, respectively with the first tube suitably coupled to the antenna circuit through coupling system or 85 circuit A. In Figure 1, a coupling network F connects the detector output to the input of the first audio-frequency amplifier tube V₆, the output of which is connected through the transformer T₁ to a pair of power tubes V₇ and V₈ 90 operating push-pull. The output circuits of the power tubes are connected in opposition through the transformer T₂ to a loud speaker LS. In Figure 2, the first audio-frequency amplifier tube V₆ is omitted, the detector output being coupled directly to the power tubes through the coupling circuit F terminating in the primary winding of transformer T₂. 95

The radio-frequency coupling circuits A to E, inclusive, are tunable over a range in frequency 100 by means of the variable condensers C₁ to C₅, inclusive, which are gang operated by a uni-control device, or control member, U₁ adapted to simultaneously adjust all circuits to the same resonance frequency.

Each screen grid tube is provided with anode 2, cathode 3, grid 4, screen grid 5, and filament 6. The filaments 6 operate in the well-known fashion to heat the cathodes 3 to the desired operating temperature and to this end may be supplied with 110

current from any suitable source. The filament supply circuits are omitted from the drawings for the sake of clarity, inasmuch as they are well understood in the art and constitute no part in the present invention.

The anodes 2 and the screen grids 5 of the radio-frequency tubes are multiplied to conductors 7 and 10 respectively, having suitable sources connected thereto for applying the necessary operating potentials to the tube electrodes. The cathodes 3 are grounded through the common resistance 11 which due to the flow of space current therethrough raises the cathodes to a positive potential above ground and is equivalent to negatively biasing the grids by the same amount since the latter are grounded.

With the form of bias provided by the potential drop in resistance 11, the negative bias on the grids is proportional to the magnitude of space current and hence functions automatically to stabilize the tube operation in that the biasing potential always varies in such manner as to oppose variations in the steady component of space current. This feature which finds a number of applications is especially useful in counteracting the effect of random variations in the mutual conductance of commercial tubes employed in the receiver. Due to the very high radio-frequency amplification employed in receivers of the type disclosed herein, it has been found that the random variations from average of the mutual conductance of the tubes is sufficient to increase the receiver sensitivity by a factor of two or three as compared to the sensitivity obtained with the average tubes, with resultant increased tendency of the receiver toward regeneration and oscillation.

By employing the automatic bias in the form of resistance 11, if the mutual conductance of the tube is increased, this change in tube characteristic will have little or no effect on the overall receiver sensitivity since the tendency for an increase in plate current resultant upon the increased mutual conductance will immediately produce an opposing effect in the form of an increased negative bias on the grid tending to reduce the mutual conductance of the tube. The net effect will be that a very slight readjustment in plate current will compensate for a rather wide variation from average in the mutual conductance of the tube with consequent stabilization in the receiver operation.

Tubes V₅–V₈, inclusive, are supplied with proper operating potentials over circuits similar to those supplying tubes V₁–V₄ and these circuits accordingly will not be described in any detail since the circuits are obvious from the drawings.

For the tubes carrying high-frequency current, the low potential point of the anode, grid and screen grid circuits are coupled to the corresponding cathodes through the high-frequency by-passing condensers 12, which serve to prevent undesirable coupling effects between the input and output sections of the tubes and thus to minimize the tendency toward regeneration.

In order to isolate the potential supply circuits of tubes V₁–V₄ from each other in so far as regenerative effects are concerned, the anode circuits thereof are separated by means of the resistors 8 interposed in the battery leads extending to conductor 7. These resistors in conjunction with the associated by-passing condensers 12 serve as sections of resistance filters preventing the passage of high-frequency currents. In a similar manner the screen grid circuits are

isolated by means of the resistors 9 interposed in the leads extending to conductor 10 cooperating with the associated by-passing condensers 12 to form filter sections. The values of the resistors 9 may be made much larger than resistors 8 due to the much smaller flow of space current in the screen grid circuits.

The electrical coupling system A comprises a pair of coupled tunable circuits interposed in cascade relation between the antenna and tube V₁ for selecting and translating the desired signal with a high degree of discrimination. The antenna and ground constitute a pair of input terminals and the grid and cathode of tube V₁ constitute a pair of output terminals, for the coupling system. The nature and magnitude of the couplings between the pair of tunable, or adjustably resonant, circuits are such as to cause the overall sensitivity and selectivity to vary in a desired manner over the tunable frequency range. Thus, to obtain substantially uniform sensitivity, i. e., constant voltage amplification as the frequency of tuning is varied, the primary coil P₁ of transformer T₁, included in the circuit with the antenna, may have an inductance sufficiently large in comparison with the antenna capacity that the natural periodicity of the antenna circuit is lower than the lowest frequency to be received. This causes the antenna circuit to respond most strongly to the lower frequencies within the tuning range and to discriminate against the higher frequencies, thereby offsetting wholly or in part the factors which are operative, in the well-known manner, to cause the voltage amplification from the primary to the tunable secondary circuit of the transformer T₁ to increase with the frequency of tuning.

By properly selecting the coupling between the primary and secondary windings the effect produced in the secondary circuit for a given signal voltage operative from the primary circuit may be caused to remain substantially constant or to increase with the frequency of tuning at a desired rate.

The effect of the primary upon the secondary circuit may be intensified or diminished by the capacity B₁ electrostatically coupling the primary and secondary circuits, the particular effect produced being dependent upon whether the capacity coupling aids or opposes the magnetic coupling. Capacity B₁ preferably comprises the inherent capacity existing between the primary and secondary turns of the transformer windings but a physical capacity may, of course, be used for this purpose. If the capacitive coupling aids the magnetic coupling, the voltage amplification will tend to increase with the frequency, whereas for the two couplings opposed the design may be such as to cause the voltage amplification to decrease with frequency.

The resonant secondary circuit coupled to the antenna circuit comprises the secondary winding S₁ of transformer T₁ included in a closed series circuit with the primary winding P₂ of a second transformer T₂ and the variable condenser C₁ for adjusting the frequency of tuning. The resonant secondary circuit S₁–C₁–P₂ is coupled through a link circuit to a second tunable circuit comprising the secondary winding S₂ of transformer T₂ and the variable condenser C₂ connected thereacross. The link circuit comprises the magnetic coupling existing between the windings P₂ and S₂ together with the electrostatic coupling provided by condenser K₁ extending between the high potential points of the two tun-

able circuits. It is seen that these two couplings are produced by fixed impedance means. The primary P_2 consists preferably of but a few turns of wire located at the low potential end of the 5 form supporting the winding S_2 .

Inasmuch as the magnetic coupling is substantially independent of frequency, whereas the electrostatic coupling increases with the frequency of tuning, the resultant effect produced 10 in the resonant circuit S_2-C_2 may by proper proportioning and poling of the elements be caused to vary both the selectivity and sensitivity in a desired manner with frequency. If, for example, it is desired to obtain a more nearly uniform 15 resonance band width over the tuning band than is obtainable with the usual type of resonant circuit, the pair of couplings of the combined electrostatic and electromagnetic coupling means should be arranged to oppose each other. Under 20 this condition, the dual coupling means produce in the resonant secondary circuit S_2-C_2 dualistic reactions which vary oppositely with frequency. Further, the coupling at the low-frequency end of the band should be adjusted to 25 optimum or slightly more than optimum coupling, the adjustment being such as to provide a resonance curve having a desired band width. As the frequency of tuning increases, the opposed 30 relations of the electrostatic and the electromagnetic couplings will cause a condition of less than optimum coupling to be obtained for the higher frequencies, thereby tending to increase the sharpness of tuning. On the other hand, the natural increase with frequency of the load or 35 effective resistance in the resonance circuit S_2-C_2 due, for example, to skin effect, eddy currents and the like, works in the opposite direction, tending to broaden the resonance curve. These two effects may by suitable design be 40 caused to balance one another and thereby to produce effects so variable with frequency as to maintain a substantially constant degree of selectivity, or resonance band width, over the entire frequency scale. The selectivity, or band 45 width, is approximately the same when the system is tuned to a frequency adjacent the upper limit of the tunable range as when tuned to a frequency adjacent the lower limit of the tunable range.

50 Inasmuch as with the arrangement described immediately above, the effective coupling between the first and second tunable circuits automatically decreases with increase in tuning frequency, the efficiency of energy transfer between 55 circuits likewise decreases in the same manner and thus tends to produce a corresponding variation in the overall voltage amplification ratio of the coupling circuit. In order to offset this effect, the coupling between primary and secondary circuits of transformer T_1 is adjusted to accentuate the voltage amplification toward the high-frequency end of the tuning range. In this way there is obtained an approximate balance of voltage gains in the two tuned circuits, as regards 60 variation with tuning frequency, which results in an approximately flat gain characteristic as well as the above noted approach to uniform selectivity over the tuning range.

To attain the desired results, the capacity K_1 65 need not necessarily be connected between the high potential points of adjacent tuned circuits, but may be tapped to an intermediate point of either coil S_1 or coil S_2 or to intermediate points of both coils.

70 The set of curves in Figure 6 are illustrative of

the results that may by proper design be obtained with a coupling network such as circuit A of Figure 1. Figure 6 gives the results of laboratory measurements made on a circuit of the type shown in Figure 7 and although the actual measurements are for the coupling network interposed between a pair of thermionic valves, it will be apparent that the same results are obtainable when the connection is between an antenna circuit and a thermionic valve as is the case for circuit A.

80 Referring now to Figure 6, curve M_1 shows the variation with the frequency of tuning of the voltage amplification as measured from the input section of tube V_x , Figure 7, to the first tuning condenser C_x . The design was such as to produce the rising amplification characteristic with frequency shown in order, as explained above, to offset the effect of decrease in coupling with frequency between the first and second tuned circuits S_1-C_x and S_2-C_y , in order to provide substantially uniform overall amplification or sensitivity.

85 Curve M_2 shows the gain characteristic or overall sensitivity for the complete network as measured from the input section of tube V_x to the input section of tube V_y for the condition that the electrostatic coupling K_y opposes the magnetic coupling P_3-S_2 , the relative proportioning of the 90 couplings being such as to provide slightly more than optimum coupling at the low-frequency limit and less than optimum coupling at the higher frequencies in order to insure substantially uniform selectivity, or at least, minimize changes in selectivity. It is apparent from curve M_2 that the 95 overall sensitivity is practically constant through the entire tuning range.

100 Curve N_1 is a measure of the total resonance band width at half-amplitude as measured across the first tuning condenser C_x ; while curve N_2 gives 105 corresponding measurements across the second tuning condenser C_y . Curve N_2 which is a measure of the overall selectivity is substantially flat, varying less than 20% over the tuning range.

110 It will be apparent from a study of the results in Figure 6 that a coupling network of the type shown in Figure 7 is admirably adapted for use in high-frequency systems since it permits the designer to control simultaneously the manner in which both sensitivity and selectivity vary with 115 frequency.

120 Returning now to Figure 1, the nature of the requirements for voltage amplification and selectivity may be such that the coupling circuit A, as described, does not fully meet all conditions 125 so that the alternative circuits may be found preferable. For example, a modification that may be utilized is to arrange the primary P_1 of transformer T_1 instead of being of high inductance to be of low inductance, thus causing the voltage 130 amplification to increase with the frequency of tuning in the well-known manner. Then by opposing the capacitive coupling K_1 to the magnetic coupling P_2-S_2 and properly proportioning the magnitudes of these coupling effects, the gain 135 or voltage ratio of the tuning system may be maintained very flat, even though the effective coupling between the two tuned circuits decreases toward the higher frequencies.

140 In Figure 2, three couplings are provided for 145 circuit, or system, A that become effective in greater or less degree, depending upon the frequency of tuning. The magnetic coupling P_2-S_2 is substantially constant over the tuning range. The effect produced by capacity K_2 and resistance 150

R_2 in shunt therewith included in resonant circuit S_2-C_2 is to provide an effective change in coupling between the two tuned circuits over the tuning range, the coupling provided by these elements being greatest in the low frequency range.

In addition, the energy dissipating impedance means K_2-R_2 tends to increase the power factor of the tuned circuit S_2-C_2 , and hence of the coupling system, at the lower frequencies, thus providing wider resonance bands at such frequencies than are normally obtainable. As the frequency of tuning increases the effective magnitude of resistance inserted in the resonance circuit S_2-C_2 by the impedance K_2-R_2 automatically decreases, due to the by-passing effect of capacity K_2 . This variation in the losses or, dissipative effect, introduced by the impedance K_2-R_2 , it will be observed, is opposed to the normal mode of variation of the resistance in the resonance circuit S_2-C_2 introduced by skin effect eddy current losses and the like, which factors tend to cause the effective resistance of the resonance circuit to increase with frequency. By properly proportioning the elements K_2-R_2 , the automatic decrease in resistance of this impedance with frequency may be employed to substantially offset the inherent increase with frequency of the resistance in the resonance circuit S_2-C_2 so that the resultant effective resistance of this circuit remains substantially constant over the entire frequency range, resulting, of course, in a correspondingly constant degree of selectivity over the tuning band.

With a circuit of the type shown at A in Figure 2, the capacity coupling K_1 may or may not be employed and may be arranged to either aid or oppose the direct capacity coupling due to the condenser K_2 , or may be made to aid or oppose the magnetic coupling P_2-S_2 , or the capacitive couplings may be used exclusively, in which case the coils P_2 and S_2 may be positioned to provide no magnetic coupling therebetween.

The antenna circuit contains a variable resistance R_1 connected in shunt with the primary winding of the transformer T_1 . This resistance constitutes a volume control for adjusting the signal intensity impressed upon the receiver.

By interposing the double-tuned circuit A between the antenna and the first amplifier tube, the desired signal may be chosen with such a high degree of selectivity that the system may be rendered substantially opaque to undesired extraneous signals while at the same time selecting the desired signal with minimum attenuation, thereby preventing intermodulation effects.

Directing attention now to the first of the inter-stage coupling networks, the output circuit of the first radio-frequency amplifier tube V_1 is in Figure 1 connected to the input of the second such tube V_2 through a coupling network B comprising an untuned transformer T_3 , the primary winding of which is connected in the anode circuit of tube V_1 with the secondary winding connected between grid and cathode of tube V_2 .

Transformer T_3 is constructed to have a substantially flat voltage amplification characteristic over the tunable range. To this end the coils are so made that the distributed capacity between turns affords natural periodicities within the tunable range. The transformer is further arranged to provide a small voltage step-up between primary and secondary circuits, and also have not too high a mutual inductance between windings, the magnetic coupling being such as to introduce the two peaks in the resonance curves adjacent

the upper and lower limits of the tuning band respectively. By winding the coils P and S of high resistance wire or by connecting a resistance such as R_3 across the primary winding, the peaks of the resonance curve may be flattened out to such an extent that the transformer provides substantially uniform response over the tunable frequency range.

An alternative design is to provide a magnetic coupling between primary and secondary windings, sufficiently close to introduce but a single resonance peak within the tuning range, and to properly damp this peak by means of the winding resistance or the shunt element R_3 to afford uniform voltage amplification.

The preferred design of this transformer is to construct the windings in several "pies" to minimize the distributed capacity between turns. These pies may comprise self-supporting coils held on an insulating mandrel or may be wound in slots cut in a separate form. The form may be enclosed in a metal cup to minimize the extent of external field. It is preferable that an iron cup be employed for this purpose since it increases the losses in the transformer circuit which, as pointed out above, are desirable in this instance.

A second volume control in the form of a variable resistance R_4 is connected in shunt with the secondary winding of the transformer T_3 . The volume control R_4 is simultaneously adjustable with the control R_1 in the antenna circuit by means of a uni-control device U_2 mechanically coupling the variable elements of these two resistances. In this way it is easily possible to secure an attenuation of 45 d. b. per control or a total attenuation of 90 d. b. This form of control is especially desirable as it provides ample signal attenuation without altering the biasing potentials applied to the tube electrodes and thus permits the tubes to be operated at the most favorable portions of their characteristics at all times.

The use of a coupling circuit B for connecting the first and second tubes, having an untunable secondary circuit, provides several advantages, without introducing serious disadvantages inasmuch as the receiver is provided with sufficient tunable circuits at other points of the circuit to furnish the desired degree of overall selectivity.

In the first place, the omission of the tuning condenser from the secondary circuit of transformer T_3 permits the insertion of the second volume control element R_4 at this point. The volume control element R_4 , of necessity, introduces a certain fixed capacity to ground equivalent to about six, or more, micro-micro-farads into the secondary circuit of the transformer, so that if a tuning condenser were connected in circuit at this point the minimum capacity of this circuit would exceed that of the other resonant circuits by the capacity of the volume control element. This would require that all of the other selecting circuits be padded up to the same minimum capacity, and would also necessitate the use of larger and more expensive variable condensers than is required with the circuit arrangement shown, since the tuning range covered by the variable condensers is determined by the ratio of the maximum to the minimum capacity. If the minimum capacity is increased, the maximum capacity must be increased in the ratio of the square of the upper and lower frequency limits in order to cover a given tuning range. This would mean, of course, that the

variable capacities would have to be constructed to have a much larger maximum capacity than required with the arrangement shown.

The coupling circuit C connecting the output 5 of the tube V_2 to the input of tube V_3 may be designed to provide substantially constant voltage amplification and selectivity over the tunable frequency range. The coupling transformer T_4 comprises a high inductance primary winding 10 P_1 and a low inductance winding P_2 of relatively few turns, both windings being magnetically coupled to the secondary winding S . The primary winding P_1 is shunted by a capacity K_3 such that the circuit K_3-P_1 has a natural 15 periodicity lower, but not greatly lower, than the lowest frequency within the tuning range. The circuit K_3-P_1 is thus capacitively reactive over the tuning range with the result that as the frequency of the tuning increases a smaller 20 and smaller percentage of the total signaling current flowing in the output circuit of tube V_2 will flow through the winding P_1 , thereby in effect automatically decreasing the coupling between windings P_1 and S as the frequency of tuning 25 increases.

Winding P_2 is so connected to the circuit K_3-P_1 that the magnetic effects with the two primary windings upon the secondary circuit are additive. Since the coupling between the primary winding P_2 and the secondary winding S is substantially constant over the frequency range while the coupling between the windings P_1 and S automatically decreases with increased frequency, the ratio of the voltage in the secondary circuit to the voltage in the primary circuit will rise with frequency, but at a rate which is under control of the designer and may be made such as to cause the amplification to remain substantially constant with frequency changes, or 40 to rise with frequency at a desired rate.

Capacity K_3 is preferably small and may in certain cases comprise the distributed capacity of the winding P_1 and the anode-to-cathode capacity of tube V_2 . In such cases, however, it is necessary to construct the winding P_1 in a special way to increase its distributed capacity, as, for example, by employing a bobbin one-half inch or more in length and layer-winding the turns of winding P_1 thereon.

50 The lower inductance primary winding P_2 comprises a relatively small number of turns which may be wound directly upon the low potential end of the form supporting the secondary winding S , or it may be wound directly over the low potential end of the secondary winding but separated therefrom by the thin sheet of insulating material such as varnished cloth or celluloid. It is preferable to space the turns of winding P_2 so that they have the same pitch as those of the 60 secondary winding S , for in this way the distributed capacity between the two windings is reduced.

The secondary winding S is tuned to resonance by means of variable condenser C_3 and has included in the resonance circuit the condenser K_4 shunted by resistance R_5 . The impedance K_4-R_5 offers a higher resistance to the low frequencies than to the high frequencies. By proper selection of the magnitudes of K_4 and R_5 the amount 70 of resistance introduced into the tuned circuit may be made to vary automatically over a wide range as the frequency of tuning changes, so that it is possible to broaden the width of the resonance band or to increase the power factor 75 of the circuit at the lower frequencies without

materially affecting, or affecting only to a small degree, the power factor at the higher frequency range. In this way it is possible to secure almost any desired resonance band ratio at the two ends of the tuning range. The results of both measurements and computation indicate that when employing a secondary circuit having a power factor of about 1%, the maximum broadening effect occurs when the resistance R_5 in ohms is about of the same order as the capacity reactance K_4 in microfarads.

80 The natural capacity B_2 existing between the primary winding P_1 and the secondary winding S of transformer T_4 may be arranged to aid or oppose the magnetic couplings between windings and thus intensify or diminish the magnetic coupling effects thereof as the frequency of tuning increases.

85 Figure 8 is illustrative of the results obtainable with coupling circuits such as network C, the curves having the same significance as those of Figure 6. The curves of Figure 8 represent the results of laboratory measurements using the circuit arrangement shown in Figure 9.

90 Curve M_3 shows the voltage amplification as measured from the input section of tube V_x to the input section of tube V_y for the condition that the dissipative impedance K_y-R_y is short circuited; while curve M_4 gives the corresponding curve with the short-circuit removed, i. e., with the impedance K_y-R_y included in the secondary circuit as shown in Figure 9. Curves N_3 and N_4 give the variations with frequency of the resonance band width at half amplitude as measured across condenser C_x for the conditions that K_y-R_y is short-circuited and is included in the secondary circuit respectively. It will be seen from these curves that by proper design a coupling circuit is obtained which provides substantially uniform sensitivity and selectivity throughout the tuning range.

95 It will be seen from a comparison of Figures 7 and 9 and the associated curves of Figures 6 and 8 respectively that two separate and distinct types of coupling circuits have been described 100 for securing uniform selectivity throughout the tuning range. The circuit of Figure 7 relates to a structure wherein a pair of tunable circuits are coupled in cascade relation. Uniform selectivity is secured by arranging the gain characteristic of the entire unit and the effective coupling between tunable circuits in such a way that over-optimum coupling is secured in the low-frequency range while under-optimum coupling is secured at the higher frequencies. In practice 105 this results in a resonance curve for the low-frequency range which has been artificially broadened in the region of resonance by from 5 to 10 kilocycles on either side of the exact resonance frequency, but which follows a normal 110 resonance curve several channels removed from the resonance frequency. At the higher frequencies of tuning the complete resonance curve is, of course, of the conventional shape.

115 This point is illustrated by the curves of Figure 10 wherein curve I shows the frequency-response characteristic of the coupling circuit when tuned to a frequency near the upper frequency limit; while curve H gives the results for tuning near the low-frequency limit. Due to the effect of over-optimum coupling, curve H has the well understood double hump in the region of resonance which thus broadens the resonance band at its base to substantially the same width as is obtained with curve I. The width of bands 120

H and I at resonance is, of course, designed to provide substantially uniform response with minimum attenuation over the essential band of audio-frequencies equivalent to one-half to one channel on either side of exact resonance. For wide departures from exact resonance, such as six or seven channels, the response curves do not have to be and, in fact, are not the same, as is indicated by the upper portions of curves 13 H and I. The curves in this region are of the conventional character, with curve H narrower in this region than curve I due to the smaller losses occurring at the lower frequencies.

Now with respect to the second method of obtaining uniform selectivity over the tuning range, accomplished by insertion of the dissipative impedance $K_y - R_y$, Figure 9, in the resonance circuit, the resultant artificial widening of the resonance band at the lower frequencies is secured by actually increasing the effective power factor of the transformer which has the effect of broadening the resonance curve throughout its entire extent at such frequencies; so that if the resonance curves for the upper and lower frequency limits of tuning coincide at one channel from exact resonance, they will be of the same order of magnitude six or seven channels removed from resonance. Thus, referring to Figure 10, this resonance curve for tuning at the lower frequency will coincide with curve I for the upper frequencies. This distinction represents a slight difference in operating characteristics between the circuits of Figures 7 and 9, although the net result will be of the same order for the two circuits insofar as side band admission or elimination is concerned.

A double-tuned circuit D is employed in the arrangement of Fig. 1 to connect the output circuit of tube V_3 with the input circuit of the fourth radio-frequency amplification tube V_4 . The output circuit of tube V_3 contains the double primary circuit of a so-called "uniform gain" transformer T_5 which is similar in operating characteristics to transformer T_4 discussed above. The high inductance primary winding P_1 is tuned by means of the fixed capacity K_{10} in shunt therewith to a frequency lower but not greatly lower than the lowest frequency to be received. The primary windings P_1 and P_2 are so connected as to produce additive effects in the secondary circuit. The magnetic coupling between the two primary windings and the secondary is so proportioned as to give a desired slope in the amplification-frequency curve of the transformer. The secondary winding S_1 is tuned to resonance by means of the variable capacity C_4 connected between ground and the high potential end of the secondary, the low potential end thereof being connected through a low inductance primary winding P_3 of transformer T_5 to ground. The secondary circuit of transformer T_5 is coupled to tunable circuit $S_2 - C_5$ through a link circuit comprising an electrostatic coupling by virtue of capacity K_5 extending between the high potential points of the secondary windings S_1 and S_2 , and an electromagnetic coupling by virtue of the mutual inductance existing between windings P_3 and S_2 .

If a substantially uniform resonance band ratio is desired for the tuning range the capacity coupling K_5 can be arranged to oppose the magnetic coupling, and the two couplings combined can be arranged to optimum or just over optimum coupling for the lowest frequency to be received.

75 The magnetic coupling should predominate

throughout the range. Then with the capacitive coupling opposing the magnetic the resulting coupling will decrease as the tuning frequency increases, thereby reducing the reaction of one resonant circuit upon the other to render the tuning sharper with increase in frequency, which effect opposes the natural tendency for the resonance curve to broaden out at the upper frequency limit, the resulting effect being such that the resonance band width is about the same throughout the frequency scale.

80 In order to insure that the coupling circuit D will provide substantially uniform voltage amplification over the tuning range, it is necessary that transformer T_5 be so designed that the voltage amplification for this transformer will increase with the frequency of tuning, as indicated in curve M_1 of Figure 6, to an extent necessary to offset the decrease in efficiency of energy transfer from the first to the second tuned circuit due to the automatic decrease in coupling therebetween.

90 The coupling circuit E connecting the output of tube V_4 to the input of the detector tube V_5 is similar in construction and operation to the coupling circuit C discussed above. It comprises the uniform gain transformer T_7 having a high inductance primary winding P_1 tuned by the shunt capacity K_{11} to a frequency below the range, and a low inductance primary P_2 . Both primaries are 105 magnetically coupled in an additive sense to the resonant secondary circuit containing in series relation the tuning condenser C_6 , secondary winding S , and the fixed capacity K_6 shunted by resistance R_6 for adjusting the resonance band 110 width.

100 Coupling circuit E is preferably arranged so that it has a higher voltage gain than the circuit just preceding it, in order that powerful local signals of low modulation percentage will not overload the tube preceding this circuit before the full output of the power tube is obtained. This condition is very likely to occur where the detector works directly into the power tubes. For 115 this same reason, it is desirable that coupling circuit E be designed for uniform gain, particularly when the tube preceding the detector tube V_5 is operating near the overload point.

120 The detector tube V_5 is of the screen grid type operating as a self-biasing tube due to connection 125 of the cathode to ground through resistance 13 which minimizes to a considerable degree the overload of the detector itself. The output of detector tube V_5 is coupled by means of circuit F to the input of a first audio-frequency amplifier 130 tube V_6 . Circuit F includes a resistance coupling network comprising resistances R_7 and R_8 included in the anode and grid circuits of tubes V_5 and V_6 , respectively, the high potential terminals of the resistances being connected through a 135 blocking condenser K_7 while the low potential terminals are connected through ground and the battery supply circuit.

140 Interposed between the output section of tube V_5 and resistance R_7 is a low-pass filter section comprising the series connected radio-frequency choke coil L_1 and the shunt capacity K_8 which functions to eliminate the radio frequency currents from the output circuit.

145 An audio-frequency high-pass filter comprising the series condensers K_9 and the shunt resistances R_9 serves to shape the audio-frequency characteristic of the system by reducing the response toward the low-frequency end of the range. The particular filter shown is merely intended to be 150

indicative of the method employed for shaping the audio-frequency characteristic. In some instances it may be desirable to utilize a high-pass or even a band-pass filter to attain a desired 5 response curve.

With receiving systems as normally constructed embodying the usual types of coupling circuits for interconnecting the radio-frequency stages, the resonance band width increases with frequency 10 of tuning due to the increase with frequency in effective resistance of the tuned circuits, producing thereby corresponding variations with frequency in the width of the side bands transmitted. If the selectivity is such as to transmit 15 at the lower frequencies of tuning a band width corresponding to the essential range of audio-frequencies, then at the higher frequencies of tuning the band width transmitted will be so broad as to introduce extraneous signals from 20 stations operating on other than the desired wave length. If, on the other hand, the selecting circuits are designed to transmit the essential 25 range of audible frequencies when the tuning is adjusted for the upper frequency limit, marked side band attenuation or trimming will occur as 30 the tuning is adjusted toward the low frequency limit due to the increase in selectivity with resultant suppression in the reproduced sound effects of the higher frequencies within the audio-range. This latter condition cannot be effectively 35 mitigated by shaping the characteristic of the audio-frequency portion of the receiver to compensate for the side band attenuation due to the variation with frequency in the amount of such attenuation.

With the present invention, however, wherein by means of the coupling circuits described, it is possible to obtain substantially uniform selectivity throughout the tuning range, the audio-frequency portion of the receiver may be designed 40 to compensate effectively for the side-band attenuation throughout the frequency range. One method of shaping the audio-frequency characteristic in this manner is by means of the low-frequency filter in coupling circuit F of Figure 1.

Figure 11 is illustrative of what may be accomplished by way of shaping the overall frequency characteristic for a receiver of the type disclosed herein. Curve G₁ which shows the response characteristic of the audio-frequency 50 stages V₆ to V₈, inclusive, is substantially flat over the essential range of audible frequencies extending from f₁ to f₂. G₂ shows the overall fidelity characteristic of the receiver with the low-pass filter of coupling circuit F omitted and 55 illustrates clearly the side band attenuation introduced due to the selecting networks at the higher audio frequencies. Curve G₃ shows the response characteristic for the audio frequency portion of the receiver including a high-pass 60 filter in the coupling circuit F suitably designed to compensate in part for the trimming caused by the selecting networks. Curve G₄ shows the final overall fidelity characteristic of the receiver with the high-pass filter included in the 65 coupling circuit F and thus shows clearly the manner in which the audio-frequency characteristic has been improved. The curves of Figure 11 are not intended to be rigorously correct, 70 but rather are illustrative of what may be accomplished by way of improving the overall receiver characteristic. It is to be stressed again that results such as shown in Figure 11 are obtainable only where, as in the present invention, the selecting networks, are such as to provide a

substantially uniform resonance band width throughout the tunable range.

The radio-frequency amplifier as a whole may be designed in several ways depending upon the operating conditions. Assume, for example, it is desired to employ tuned circuits having about the characteristics now commonly employed in broadcast receivers which have a power factor of about 1%, then by broadening the resonance band of the individual stages at the low-frequency range, while leaving the resonance band at the high-frequency range, substantially unaffected, the ratio over the whole range will remain uniform. If the conventional number of three or four tuned circuits were to be employed, this broadening of the resonance band might impair the overall selectivity, but when employing coils having a 1% power factor, a larger number of tuned circuits will be employed than has heretofore been the practice, so, in this way, the 95 desired overall selectivity can be secured.

Where a large number of tuned circuits are employed, theory and experiment indicate that the peak of the resonance curve may be quite broad while for conditions slightly off resonance 100 the sides are very steep. This steepness of the sides of the resonance curve (just as at the low frequency range of present commercial receivers) tends to attenuate the side bands so that for the higher audio frequencies there is very 105 little response. This undesirable condition may be corrected wholly or in part by the present invention because the resonance band width is made uniform over the tuning range in the manner explained above and the attenuation resulting at the higher audio frequencies may be compensated for in the audio system by either reducing the gain characteristic of the audio system at the low frequency range such as by interposition of the high pass filter circuit in the detector 110 output or by increasing the high frequency response.

The present invention may be successfully practiced when employing the conventional number of three, four or five tuned circuits by 120 using tuned resonant circuits of a lower power factor than 1%. This may be accomplished by employing larger diameter coils than now commonly used and winding the secondary inductances with larger sized wire spacing the turns, or using radio-frequency cable rather than solid 125 wire. In this way it is possible to reduce the power factor of the tuned transformers to .5% or lower. This practice, whether employed with three or a greater number of tuned circuits, is 130 likely to seriously impair the quality of reproduction because of side band cutting, but as previously described, the effects may easily be compensated for by proper shaping of the audio characteristic.

In many cases it is desirable to reduce the high-frequency response of the audio system, particularly above 3000 or 4000 cycles. This may be very conveniently accomplished in the present invention by proper selection of the number and power factor of the tuned circuits so that the side-band attenuation of the radio-frequency portion of the amplifier becomes effective in the region of 3000-4000 cycles, thus automatically giving the desired overall fidelity response. 135

Experience has indicated that where the sensitivity of a receiver is high, it is preferable to slope the gain characteristic so that it has about a 2:1 ratio; that is, it has about twice the sensitivity at the low-frequency as at the high-fre- 140 145 150

quency range. By sloping the curve in this way, the stability and freedom from oscillation remains about uniform. This condition may, of course, not be desirable for all circumstances but 5 may easily be modified as conditions warrant. Figure 2 shows a circuit designed in this manner.

In Figure 2 transformer T_1 of coupling circuit A is provided with a low inductance primary winding included in the antenna circuit, thus 10 causing the voltage amplification from primary to secondary circuit to increase with frequency. The resonant secondary circuit of transformer T_1 is coupled to the secondary circuit of transformer T_2 capacitively by means of condenser K_1 , 15 magnetically by the mutual inductance between windings P_2 and S_2 , and conductively by connection of the low potential terminals of windings P_2 and S_2 . The proportioning and poling of the various couplings and the design of the 20 dissipative circuit K_2-R_2 included in the resonant secondary circuit S_2-C_2 , is such as to provide substantially uniform voltage amplification and constant selectivity over the tunable range.

Coupling circuit B connecting tubes V_1 and 25 V_2 in cascade relation in this instance comprises a uniform gain transformer T_4 similar to that of coupling circuits C and E of Figure 1. The volume control resistor R_4 is in this instance bridged across the primary circuit of transformer T_4 30 since, for reasons explained above, it is undesirable to have this element bridging the tunable secondary circuit. The connection of control R_4 across the primary circuit of transformer T_4 necessitates insulation of all active portions of 35 the control above ground potential, and in this respect does not provide so desirable an arrangement as the circuit of Figure 1.

It is, of course, not essential that transformer T_4 be of the uniform gain type. By employing 40 such a transformer, however, it is possible to design the amplification characteristic to compensate for the capacitive reactance introduced into the primary circuit due to employment of the volume control and obtain substantially uniform 45 resultant amplification over the tuning range. This result is attained by designing the transformer so that the impedance of the primary transformer circuit is proportionally higher at the high-frequency than at the low-frequency 50 end of the tuning range. As a consequence, when the volume control is connected in circuit, it tends to equalize the impedance over the entire range, thus producing uniform amplification. The resistor R_5 and shunt capacity K_4 , included 55 in the resonant circuit, are selected of such values as to provide about the same or a slightly wider resonance band at the low than at the high frequency tuning range.

The broadly tuned aperiodic transformer T_3 60 now comprising circuit C coupling the output of tube V_2 with the input to tube V_3 may be given a voltage amplification slope favoring the low-frequency over the high-frequency response in about a 2:1 ratio in order to provide a corresponding overall frequency-response characteristic 65 for the radio-frequency amplifier.

The double-tuned circuit D of Figure 2 employs a uniform gain type of transformer T_{10} in the output circuit of tube V_3 , the gain-frequency 70 characteristic of which may be given a desired slope. The primary winding P_1 is wound to a relatively high inductance and in such manner that preferably the natural capacity K_{13} between turns in conjunction with the anode-cathode capacity of tube V_3 is sufficient to render the pri-

mary circuit resonant at a frequency slightly below the tuning range. If necessary, of course, a separate condenser may be used to supplement the natural capacity K_{13} in order to provide the required natural periodicity of the primary circuit. The primary P_1 is coupled magnetically to the secondary winding by means of the mutual inductance between windings and also capacitively by means of condenser K_{12} connecting the high potential terminals of the two windings.

80
85

The primary winding due to the capacity in shunt therewith is capacitively reactive over the tuning range, and hence has a falling impedance characteristic for increases in frequency, which effect opposes the gain in voltage amplification with frequency, which in the absence of other factors would exist. This opposing effect is further intensified due to the automatic decrease in effective coupling between the primary and secondary circuits with increase in frequency resulting from the shunting effect of capacity K_{13} . The capacitive coupling K_{12} may be arranged, depending upon the respective polarities of the high potential terminals of the primary and secondary windings, to either aid or oppose the magnetic coupling in the secondary circuit, the particular arrangement utilized being determined by the desired slope of the gain-frequency characteristic to be attained. In the present instance it is desirable to have a substantially uniform 100 frequency-gain characteristic for the transformer T_{10} and accordingly the capacitive coupling K_{12} is arranged to aid the magnetic coupling, since otherwise the rapid decrease in impedance of the primary circuit and the automatic decrease in 105 effective coupling between the primary and secondary windings would cause the voltage amplification to decrease with increase in the tuning frequency.

90
95
100
105

The resonant secondary circuit of transformer T_{10} includes the primary winding P_2 of transformer T_5 which is magnetically coupled to the secondary winding S_2 thereof. The secondary winding S_2 is, in turn, included in a resonant circuit S_2-C_5 which contains the dissipative impedance $K_{14}-R_{12}$ proportioned to maintain an approximately constant resonance band width over the tuning range in the manner explained above. Thus, the circuit D when properly designed will have a substantially uniform overall 120 frequency-gain characteristic, and likewise a substantially constant degree of selectivity over the tuning band.

115
120
125

The double-tuned circuit D of Figure 2 is, of course, an alternative arrangement to that of Figure 1, the transformer T_5 in one instance and T_{10} in the other controlling the variation with frequency of the voltage amplification in an essentially similar fashion. It is to be understood that a transformer such as T_{10} could, in general, with proper design modifications be used for coupling other portions of the receiver where the "uniform gain" type of transformer is desirable as, for example, in the coupling circuits C and E of Figure 1. Also, various other types of "uniform gain" coupling circuits are available which could be utilized to replace such transformers, as, for example, T_4 , T_5 or T_{10} . Examples of such circuits are shown in Figures 3, 4, and 5. In each of these figures I represents the input terminals and O the output terminals.

135
140
145
150

In Figure 3 there is provided only a magnetic coupling between the primary winding P and the secondary winding S. The primary winding P is of relatively high inductance and is tuned

5 by means of the natural capacity K_{17} between turns or by a physical condenser to a frequency slightly below the tuning range. The primary circuit has therefore a falling impedance characteristic over the tuning range with increase in frequency, and further as the frequency increases there is an automatic decrease in effective coupling between the primary and secondary circuits due to the shunting effect of capacity 10 K_{17} . Both of these effects offset the inherent tendency which would otherwise exist for the amplification to increase with frequency.

15 In Figure 4 the primary circuit winding P is again wound to a relatively high inductance and is tuned by means of the natural capacity K_{18} between turns to a frequency slightly below the tuning band. In this instance, however, the primary circuit is coupled only capacitively to the secondary circuit by means of the coupling condenser K_{19} connecting the high potential terminals 20 of the primary and secondary windings P and S respectively. As the frequency of tuning increases, the primary winding P , due to its falling impedance characteristic tends to produce 25 an ever decreasing effect in the secondary winding S . Opposed to this, however, is the effect of the capacitive coupling between the primary and secondary circuits, which increases with frequency, so that by properly selecting the impedance characteristic of the primary winding P and the magnitude of the coupling capacity K_{19} , the frequency-gain curve for the network may 30 be sloped in a desired manner.

35 In the circuit of Figure 5 the primary winding P is of the same general order of inductance as the secondary winding and is coupled magnetically thereto by means of mutual inductance M between windings, and capacitively by means of condenser K_{16} extending between the high potential terminals of the two windings. It will 40 be observed that in this instance the primary winding is not resonant at a frequency below the tuning range, and accordingly its impedance will increase with frequency, thus tending to give 45 a positive slope to the gain-frequency characteristic. While the capacitive coupling K_{16} may be arranged to either aid or oppose the magnetic coupling or may not be employed at all, in general, it will be desirable to have the capacity coupling oppose the magnetic coupling in order 50 to provide substantially uniform amplification over the tuning band.

55 The high gain circuit E of Figure 2 is arranged to have a substantially flat amplification curve. By the proper selection of the condenser K_8 and resistor R_8 the selectivity characteristic is made either uniform or slightly broader at the low-frequency than at the high-frequency range.

60 Summing up the characteristics for the radio frequency amplifier, the overall sensitivity will have the desired 2:1 ratio favoring the low frequencies, while the overall selectivity will be substantially uniform over the tuning range.

65 In Figure 2 the first stage of audio-frequency amplification shown in Fig. 1 is omitted, the circuit F serving to connect the detector output directly through transformer T_8 to the power tubes V_7 and V_8 connected push-pull.

70 With the type of receiver shown in Figures 1 or 2 the sensitivity is made very high and to do this practically it is necessary to so position the parts, arrange the wiring and provide shielding so as to effectively eliminate extraneous couplings from stage to stage and from the input to the 75 output.

Wherever possible, elements operated at low radio-frequency potentials such as by-pass condensers, audio-frequency transformers, etc., are physically interposed between adjacent high potential points and their shielding or casings 80 grounded so that this mass acts to minimize capacitive fields. The elements of the various stages are preferably individually shielded by metal cans. For example, all the elements are mounted on a metal base and then the tuning condenser element is shielded by a metal can secured to the base so as to completely eliminate 85 capacitive couplings between adjacent condensers and between condensers and other parts of the receiver.

90 The various tuning coils are preferably individually shielded by grounded metal cans. The amplifying tubes may be interposed between the metal cans to effectively shield the exposed portions from one another or they may be shielded by individual cans.

95 To eliminate common couplings in the chassis pan, wires and tuning condenser, etc., it has been found extremely helpful to connect, for example, the low potential terminal of each transformer 100 secondary winding directly to its own tuning condenser rotor by means of a separate wire and brush contact rather than to ground such terminals to the chassis pan and rely on the connection from the pan to the condenser for 105 a proper return path. It has also been found that when employing by-pass condensers, such as for the "A", "B" and "C" voltages, and also the plate by-pass for the detector, that these 110 connections should be made directly to the cathode of the tube under consideration rather than to ground. In this way common couplings resulting from currents flowing in the chassis pan are eliminated.

115 Couplings of the nature just discussed are especially important in a design such as Figures 1 and 2, because the desired couplings between adjacent stages are small and extraneous or unknown couplings might easily vitiate the desired effects.

120 I claim:

1. A high frequency electrical coupling system having input and output terminals for interconnecting successive portions of a multi-stage thermionic radio receiver, comprising, at least one 125 resonant circuit tunable throughout a frequency range, and fixed impedance means included in said coupling system producing effects so variable with frequency as to maintain the resonance band width of said coupling system substantially 130 constant throughout said tunable frequency range.

2. A high frequency electrical coupling system having input and output terminals for interconnecting successive portions of a multi-stage thermionic radio receiver, comprising, at least one 135 resonant circuit tunable throughout a frequency range, and fixed impedance means included in said coupling system producing effects so variable with frequency as to render the selectivity of 140 said coupling system when tuned to a frequency adjacent the upper limit of said tunable range substantially equal to the selectivity of said coupling system tuned to a frequency adjacent the lower limit of said tunable range.

145 3. A tunable high frequency electrical coupling circuit adapted to interconnect successive portions of a multi-stage thermionic radio receiver, comprising, a resonant secondary circuit, and a primary circuit including a plurality of fixed 150

impedance means so arranged and coupled to said secondary circuit as to produce effectively in said secondary circuit dualistic reactions proportioned to maintain the selectivity of said coupling system substantially constant throughout a tunable frequency range.

4. A tunable high frequency electrical coupling system adapted to interconnect successive portions of a multi-stage thermionic radio receiver, comprising, a resonant secondary circuit, and a primary circuit including a plurality of fixed impedance means so arranged and coupled to said secondary circuit as to produce effectively in said secondary circuit dualistic reactions which vary oppositely with frequency at such rate as to maintain the selectivity of said coupling system substantially constant throughout a tunable frequency range.

5. A tunable high frequency electrical coupling system adapted to interconnect successive portions of a multi-stage thermionic radio receiver, comprising, a resonant secondary circuit, and a primary circuit including fixed impedance means so arranged and coupled to said secondary circuit as to produce effectively in said secondary circuit dualistic reactions which vary oppositely with frequency at such rate as to automatically adjust the effective coupling between primary and secondary circuits from optimum or slightly more than optimum coupling at the low frequency end of the tuning range to less than optimum coupling at the upper frequency limit thereof for reducing variations in selectivity otherwise present in said coupling system as the tuning is adjusted throughout the tunable frequency range.

6. A tunable high frequency electrical coupling system adapted to interconnect successive portions of a multi-stage thermionic radio receiver, comprising, a resonant secondary circuit, and a primary circuit including fixed impedance means so arranged and coupled to said secondary circuit as to produce effectively in said secondary circuit dualistic reactions which vary oppositely with frequency at such rate as to automatically adjust the effective coupling between primary and secondary circuits from such a magnitude greater than optimum coupling at the low frequency end of the tunable range to such a magnitude less than optimum coupling at the upper frequency end of the tunable range as to maintain the selectivity of said system substantially constant throughout the tunable frequency range.

7. A high frequency electrical coupling system including at least one resonant circuit tunable throughout a frequency range, and fixed impedance means included in said resonant circuit producing effects so variable with frequency as to provide approximately the same resonance band widths for said coupling system at the upper and lower frequency limits of said tunable range.

8. A high frequency electrical coupling system including at least one resonant circuit tunable throughout a frequency range, and fixed impedance means included in said resonant circuit producing effects so variable with frequency as to minimize changes in selectivity of said coupling system as the tuning is adjusted throughout said frequency range.

9. A high frequency electrical coupling system including at least one resonant circuit tunable throughout a frequency range, and energy dissipating impedance means decreasing in dissipative effect with increase in frequency included in said resonant circuit for reducing variations in selec-

tivity of said coupling system throughout said tunable range.

10. A high frequency electrical coupling system including at least one resonant circuit tunable throughout a frequency range, and fixed impedance means comprising resistance shunted by capacity serially interposed in said resonant circuit for reducing variations in selectivity of said coupling system as the tuning is adjusted throughout said frequency range.

11. In an electric signaling arrangement a tunable coupling system for coupling two portions thereof, adapted to respond to a uniform band width of frequencies over a wide tuning frequency range, said coupling system comprising a pair of input terminals and a pair of output terminals, an inductance element connected between said pair of input terminals, a pair of adjustably resonant circuits coupled together by a dual coupling, a control member for simultaneously adjusting the resonance frequencies of said circuits, the first of said resonant circuits being electromagnetically coupled to said inductance element and the second of said resonant circuits being connected to said output terminals, said dual coupling being proportioned to provide a resultant coupling which increases as the tuning frequency of said resonant circuits is decreased, whereby the band width to which said system is responsive remains substantially uniform over said tuning range.

12. A combination according to claim 11 in which said dual coupling is a combined electrostatic and electromagnetic coupling.

13. A combination according to claim 11 in which said dual coupling is substantially less than optimum when the resonant circuits are tuned to high frequencies and becomes greater as the tuning frequency is decreased.

14. In an electric signaling arrangement, a pair of vacuum tubes each having an input circuit and an output circuit, a tunable coupling system adapted to respond to a uniform band width of frequencies over a wide tuning range, for coupling the output of one tube to the input of the other tube, said system comprising an inductance element connected across said latter output, a pair of adjustably resonant circuits coupled together by a dual coupling, a control member for simultaneously adjusting the resonance frequencies of said resonant circuits, the first of said resonant circuits being electromagnetically coupled to said inductance element, the second of said resonant circuits being connected to said input circuit, said dual coupling being proportioned to increase as the tuning frequency of said resonant circuits is decreased, whereby the band width to which said system is responsive remains substantially uniform over said tuning range.

15. An electric coupling system comprising a pair of resonant circuits tunable to the same frequency over a wide range of frequency, a control member for simultaneously tuning said circuits, means producing a pair of couplings between said circuits which vary with frequency in an opposite manner relatively to each other, said couplings being proportioned to increase when the frequency of tuning is decreased whereby the width of the frequency band transmitted by said system is maintained substantially uniform over the tuning range.

16. An electric coupling system according to claim 15 in which said pair of couplings is an electromagnetic coupling and an electrostatic coupling.

17. An electric coupling system according to 150

- claim 15 in which the means producing said pair of couplings are fixed.
18. An electric coupling system comprising a pair of resonant circuits tunable to the same frequency over a wide frequency range, a control member for simultaneously tuning said circuits, means producing an electromagnetic coupling and means producing an electrostatic coupling, between said circuits, said couplings being proportioned to provide a resultant coupling between said circuits which is substantially less than optimum when said circuits are tuned to a high frequency and becomes greater as said circuits are tuned to lower frequencies.
19. In an electric signaling arrangement, a tunable coupling system adapted to respond to a uniform band width of frequencies over a wide tuning frequency range, said coupling system comprising a pair of input terminals and a pair of output terminals, an inductance connected between said pair of input terminals shunted by such capacity that it is naturally resonant at a frequency lower but not greatly lower than the lowest frequency of said tuning range, a pair of adjustably resonant circuits coupled together by a dual coupling, a control member for simultaneously adjusting the resonance frequencies of said circuits, the first of said resonant circuits being electromagnetically coupled to said inductance element and the second of said resonant circuits being connected to said output terminals, said dual coupling being proportioned to provide a resultant coupling which increases as the tuning frequency of said resonant circuits is decreased, whereby the band width to which said system is responsive remains substantially uniform over said tuning range.
20. In an electric signaling arrangement, a tunable coupling system adapted to respond to a uniform band width of frequencies over a wide tuning frequency range, said coupling system comprising a pair of input terminals and a pair of output terminals, an inductance element connected between said pair of input terminals, a pair of adjustably resonant circuits coupled together by a dual coupling, a control member for simultaneously adjusting the resonance frequencies of said circuits, the first of said resonant circuits being electromagnetically coupled to said inductance element and the second of said resonant circuits being connected to said output terminals, said dual coupling being proportioned to provide a resultant coupling which is over-optimum at the lower frequencies of said tuning range.
- range and decreases as the tuning frequency is increased, whereby the band width to which said system is responsive remains substantially uniform over said tuning range.
21. A high frequency electrical coupling system comprising a resonant circuit, means for variably tuning said system over a range of frequency and means for causing the power factor of said system to increase when the frequency to which said system is tuned decreases.
22. A high frequency electrical coupling system comprising a resonant circuit, means for variably tuning said system over a range in frequency, and means for introducing resistance into said circuit which effectively increases in magnitude with decreasing frequency.
23. A high frequency electrical coupling system comprising a tunable circuit, means for variably tuning said circuit over a range in frequency, means introducing resistance into said circuit and means automatically varying the effective magnitude of said resistance inversely with respect to the tuning frequency, whereby a substantially constant degree of selectivity is maintained over said frequency range.
24. A high frequency electrical coupling system for translating a band of signal frequencies from an input circuit to an output circuit, said system comprising a variable tuning element for selecting the position of said frequency band over a considerable range in frequency, a resistance, the magnitude of which is dependent upon the adjustment of said tuning element and means for simultaneously varying said tuning element and the magnitude of said resistance so that when said frequency band is moved higher in the frequency range the effective magnitude of said resistance is decreased, whereby a substantially constant band width may be maintained over said range.
25. A high frequency electrical coupling system tunable throughout a range in frequency, adapted to interconnect successive portions of a multi-stage amplifier, said system comprising a primary circuit and a tunable resonant secondary circuit inductively coupled to said primary circuit and means associated with said secondary circuit for introducing losses therein which vary as said circuit is tuned throughout said range, to maintain substantially constant the selectivity of said system throughout said tunable frequency range.

“7. A high frequency electrical coupling system including at least one resonant circuit tunable throughout a frequency range, and fixed impedance means included in said resonant circuit producing effects so variable with frequency as to provide approximately the same resonance band widths for said coupling system at the upper and lower frequency limits of said tunable range.”

“15. An electric coupling system comprising a pair of resonant circuits tunable to the same frequency over a wide range of frequency, a control member for simultaneously tuning said circuits, means producing a pair of couplings between said circuits which vary with frequency in an opposite manner relatively to each other, said couplings being proportioned to increase when the frequency of tuning is decreased whereby the width of the frequency band transmitted by said system is maintained substantially uniform over the tuning range.”

“16. An electric coupling system according to claim 15 in which said pair of couplings is an electromagnetic coupling and an electrostatic coupling.”

“18. An electric coupling system comprising a pair of resonant circuits tunable to the same frequency over a wide frequency range, a control member for simultaneously tuning said circuits, means producing an electromagnetic coupling and means producing an electrostatic coupling, between said circuits, said couplings being proportioned to provide a resultant coupling between said circuits which is substantially less than optimum when said circuits are tuned to a high frequency and becomes greater as said circuits are tuned to lower frequencies.”
